IRON HOLDER

Filed April 7, 1931

By *Lacey, Lacey,* Attorneys

UNITED STATES PATENT OFFICE

HAROLD E. RIFFEY, OF VIRDEN, ILLINOIS

IRON HOLDER

Application filed April 7, 1931. Serial No. 528,387.

This invention relates to iron holders, and more particularly to an iron holder constituting an attachment for an ironing board.

One object of the invention is to provide an iron holder which may be easily applied to an ironing board at one end thereof and very firmly secured to the board in such position that an iron may be very easily moved on to the holder when the iron is not in use.

Another object of the invention is to so construct the iron holder that when it is applied to an ironing board an iron may be slid from the board on to the holder or from the holder back on to the board, thereby making it unnecessary to lift the iron when moving it on to or off the holder.

Another object of the invention is to eliminate any danger of causing the cover for an ironing board to be scorched in case the holder becomes very hot due to an iron resting upon the holder for some time and to also make it unnecessary to tilt the iron upwardly when it is moved on to the holder in order to prevent the holder from becoming overheated and thereby prevent a person's wrist from becoming tired when ironing.

Another object of the invention is to so form the holder that it may be easily applied to an ironing board or removed therefrom for transfer to another board, and also permit a portion of the holder to be detached when it is necessary to apply a new cover to an ironing board.

The invention is illustrated in the accompanying drawing, wherein:

Figure 1 is a top plan view showing the iron holder applied to an ironing board.

Figure 2 is a bottom plan view of the iron holder and board,

Figure 3 is a sectional view taken along the line 3—3 of Figure 2, and

Figure 4 is a fragmentary view showing the manner of preventing the securing bolts from turning.

The iron holder which is indicated in general by the numeral 1 is usually applied to an ironing board 2 at one end thereof as shown, but it is to be understood that it could be applied at one side of the ironing board if so desired. The usual cover 3 is

provided for the ironing board and may be tacked against the underface of the board after being drawn tightly into place as shown in Figure 2 or laced or otherwise secured. The platform or shelf 4 of the iron holder is formed of strong sheet metal and has marginal portions bent upwardly to form an abutment flange 5 extending along the sides and outer end of the shelf in order to prevent danger of an iron slipping off of the same when moved on to the shelf. It should be noted that the metal forming the flange is bent back upon itself as shown in Figure 3 in order to provide this flange with a smooth upper edge and eliminate danger of a person being cut by contact with the upper end of the flange. At its inner end the sheet of metal from which the shelf or platform is formed is bent downwardly to form a depending lip or flange 6.

In order to support the shelf, there has been provided bars 7 formed of angle metal. These bars are of sufficient length to be disposed longitudinally of the ironing board with portions projecting outwardly therefrom as shown in Figures 2 and 3 and the end portions of these bars which extend beneath the ironing board are formed with openings to receive bolts 8 passing through openings formed in the ironing board and having their heads countersunk.

Sockets 9 are formed in the metal platform or shelf 4 to receive and countersink the heads of bolts 10 which extend downwardly through openings formed in the bars 7. These bolts are held against rotation by ribs 10' and carry sleeves 11 which serve to retain the shelf in proper spaced relation to the bars when the securing nuts 12 of the bolts are tightened. Beneath the shelf is disposed a plate 13 formed of strong metal which rests upon the bars 7 and has one end portion bent upwardly as shown at 14 to form a flange which bears against the end of the ironing board.

This flange has its upper portion bent to form a downwardly inclined lip 15 to overlap the ironing board and by referring to Figure 3 it will be seen that this lip bears against the adjacent end of the cover 3. Upon the

plate 13 is placed a sheet 16 of asbestos or other suitable heat insulating material and this sheet has a portion bent upwardly as shown at 17 to bear against the flange 14 with its upper portion engaged between the flange 14 and the flange or lip 6 of the shelf. Therefore the shelf cannot have direct contacting engagement with the flange 14 even if the shelf becomes very hot due to a hot iron resting thereon, the flange 14 and its lip 15 will not become overheated and there will be no danger of the ironing board or its cover becoming scorched. A retainer plate 18 rests upon the asbestos sheet 16 and has one end portion bent upwardly as shown at 18' to bear against the lower portion of the up-turned portion 17 of the asbestos sheet. By referring to Figure 3 it will be seen that certain of the bolts 10 pass through the plates 13 and 18 and the asbestos sheet 16 as well as through the bars 7 with the sleeves 11 of these bolts resting upon the plate 18. Therefore when the nuts for these bolts are tightened the plates and the asbestos sheet 25 will be firmly held against the bars and the lip 15 will be drawn into tight binding engagement with the portion of the cover or ironing board which it overlaps. By this arrangement the iron holder will be very firmly secured to the ironing board.

In order to permit the shelf and the plates and asbestos sheet to be detached from the bars 7 after removing the nuts 12 without the plates and asbestos sheet slipping out of proper position beneath the shelf, there has been provided a fastener 19 which may be a bolt or rivet. This fastener which is preferably a rivet has its head countersunk in a socket 20 and carries a sleeve 21 which bears against the plate 18 when a head is formed at the lower end of the fastener or a securing nut applied thereto. By this arrangement the plates and the sheet of asbestos between them will be permanently connected with the shelf or platform and will remain in place when the nuts 12 are removed and the shelf lifted upwardly.

When the iron holder is in use it is applied to an ironing board as shown and will be firmly held in place. The iron is used in the usual manner and when not in use is slid on to the shelf. It is therefore not necessary to lift the iron in order to place it upon a holder and also not necessary to tilt it to an upright position in order to prevent danger of scorching an ironing board or its cover. It is also not necessary to tilt the iron into position for use or lift it from a holder when it is to be again used. This removes strain from a person's wrist and prevents the wrist from becoming sore or tired when ironing. The device can be easily removed or transferred to another board.

While it has been shown applied to an ironing board of the type which is rested upon a

table or other support, when in use it will be readily seen that it can be also applied to an ironing board having folding legs, or hinges may be applied to the outer end of the bars 7 in order to hingedly connect the ironing board with a wall support or the door of a cupboard.

What is claimed is:

1. In combination with an ironing board having a cover, an iron support comprising a shelf, arms secured against the under face of said board and projecting longitudinally from the board beneath said shelf, means for detachably connecting the shelf with said arms and retaining the shelf spaced above the arms, and a member carried by said arms and provided with a lateral lip bearing against the cover for the entire width of the ironing board, said member serving to brace the arms against downward strain and guide an iron onto said shelf. 75

2. In combination with an ironing board having a cover, an iron support comprising a shelf, arms secured against the underface of said board and projecting from the board beneath said shelf, means to connect said shelf with said arms and retain the shelf spaced above the arms, a plate carried by said arms and having a flange extending upwardly and provided with a lateral lip overlapping and bearing against said cover for the entire width of the ironing board and a sheet of heat insulating material extending between the flange and shelf to protect the cover from heat. 90

3. An iron holder comprising a shelf, arms beneath said shelf projecting from the inner end thereof and adapted to be secured against the underface of an ironing board, means to connect said shelf with said arms and support the shelf above the arms, and a plate secured upon said arms and having a portion bent to form a flange extending upwardly to bear against an edge face of an ironing board and terminating in a downwardly inclined lip to engage over the ironing board for the entire width thereof and brace the arms against downward pressure. 105

4. An iron holder comprising a shelf, arms beneath said shelf projecting from the inner end thereof and adapted to be secured against the underface of an ironing board, bolts extending through the shelf and arms, sleeves about said bolts retaining the shelf spaced above said arms, a plate upon said arms beneath said shelf and having an end portion bent upwardly to form a flange to bear against an end of an ironing board and then bent to form a lip to overlap the board, a sheet of heat insulating material resting upon said plate and having an end portion extending upwardly against said flange and engaged between the flange and adjacent end of said shelf, and a reinforcing plate covering said sheet. 115

120

125

130

5. An iron holder comprising a shelf, arms beneath said shelf projecting from the inner end thereof and adapted to be secured against the underface of an ironing board, bolts extending through the shelf and arms, sleeves about said bolts retaining the shelf spaced above said arms, a plate upon said arms beneath said shelf and having an end portion bent upwardly to form a flange to bear against an end of an ironing board and then bent to form a lip to overlap the board, a sheet of heat insulating material resting upon said plate and having an end portion extending upwardly against said flange, the adjacent end of said shelf being bent downwardly to form a flange, the upturned portion of said sheet being engaged between the flanges of the plate and shelf, and a reinforcing plate upon said sheet having a portion bent upwardly to bear against the upturned portion of said sheet, certain of said bolts being engaged through the plates and insulating sheet to retain the same in place.

In testimony whereof I affix my signature.

HAROLD E. RIFFEY.
